Inventor:

E. Bonham

UNITED STATES PATENT OFFICE.

ELEM BONHAM, OF BRANTFORD TOWNSHIP, BRANT COUNTY, CANADA.

IMPROVEMENT IN WASHING-MACHINES.

Specification forming part of Letters Patent No. 130,972, dated September 3, 1872.

SPECIFICATION.

I, ELEM BONHAM, of the township of Brantford, in the county of Brant, in the Province of Ontario, Canada, have invented certain Improvements in Machines for Washing Clothes.

Nature and Object of the Invention.

My invention consists in using a frame to lie on the bottom of the box or case into which the clothes are put to be washed. In the said frame rollers are set on which the clothes to be washed lie, and are rubbed and turned over by feet or beaters until clean; the heavy sediment falls between the rollers and lies on the bottom of box or case, and is not rubbed down with the clothes. When it is desired to increase the size of the machine a board is drawn out from the front of the roller-frame and the frame slipped forward.

Description of the Accompanying Drawing.

Figure I is a side elevation of the machine. Fig. II is a section showing inside of box with roller-frame, rollers, and altering-board. Fig. III is the front of altering-board.

General Description.

A shows box which contains the clothes to be washed. B is a board at the end of roller-frame C, which may be drawn out and the frame slipped forward, thus increasing the size of the machine. C is the roller-frame, which is set in box A. D D show rollers of wood,

which work in each side of frame C. E is a double crank. F is a block, fastened on a post, and covers a collar or ruff on the end of double crank E, and thus keeps crank E as required. G is a fly-wheel on crank-shaft, by which the machine is driven; H H, upright bars, fastened on each side of box A. I is a bar, connecting bars H; M, radial bars, to which feet or beaters N are attached. N shows blocks of wood fastened to the ends of radial bars M. They are beveled at the front and fluted across to rub and turn the clothes; O O, connecting-rods from double crank E to radial bars M, which cause them to oscillate on connecting-bar I; and feet or beaters N rub and turn the clothes on rollers D. P is front cover, hinged to cover Q. Both require to be raised when a wringer is used. R is a plug, by which the water is drawn from box A.

I do not claim as my invention the feet or beaters N, worked by double crank E and radial bars M.

What I claim as my invention and improvement is—

The arrangement of the roller-frame C and rollers D, and the board B, by which the frame may be slipped forward or drawn back, in the manner shown and described.

Brantford, 25th March, 1872.

ELEM BONHAM.
